UNITED STATES PATENT OFFICE.

PETER N. STANKOVITCH, OF SEATTLE, WASHINGTON.

BLASTING POWDER.

1,412,319.

Specification of Letters Patent. Patented Apr. 11, 1922.

No Drawing.

Application filed July 14, 1921. Serial No. 484,763.

To all whom it may concern:

Be it known that I, PETER N. STANKOVITCH, a citizen of the United States, residing at Seattle, in the county of King and State of Washington, have invented certain new and useful Improvements in Blasting Powder; and I do declare the following to be a full, clear, and exact description of the invention, such as will enable others skilled in the art to which it appertains to make and use the same.

This invention relates generally to explosives and particularly to an improved explosive or blasting powder capable of general use, but particularly suitable for light blasting, such as stump blasting, land clearing, and blasting hardpan or cemented gravel. It may also be used effectively for blasting purposes in coal and quartz mines. The improved powder can be handled and used with a considerable amount of safety. It is not susceptible to deterioration, and hence it may be handled, used and stored regardless of climatic conditions, and it will retain its strength for an indefinite period of time.

The improved powder consists of nitroglycerin, dinitrotoluene, sodium nitrate, flour, middlings and sulphur. A cheap or lower grade of flour may be used, but a good grade of middlings should be selected. The sulphur used should be crude sulphur and must be in a finely powdered state.

The ingredients may be mixed together in various proportions according to the particular use for which the powder is intended. A powder having the proper strength and other qualities for light blasting, such as stump blasting, land clearing, and blasting hardpan or cemented gravel, may be obtained by mixing the ingredients in the following proportions, viz.—

Nitroglycerin	10.0%
Dinitrotoluene	2.0%
Sodium nitrate	65.5%
Flour	8.0%
Middlings	6.0%
Sulphur	8.5%
Total	100.0%

Where a more powerful powder is required, the proportions of the nitroglycerin and dinitrotoluene may be increased up to 20%. It then can be suitably used for mining purposes, such as for hard coal min-

ing and for mining generally in quartz mines and flat formation mines where the formations are generally soft and the rocks are of medium hardness, such as is shale, slate and sandstone.

Where a less powerful powder is desired, only about 10% of the nitroglycerin and dinitrotoluene need be used. This makes a very cheap blasting powder suitable for blasting hardpan and loosening up the ground or soil where steam shovels are used or where grading is being done.

The powder can be made in five hundred or one thousand pound batches, and in mixing a thousand pound batch of the powder of the first of the foregoing specified powders, the ingredients should be mixed together in the following proportions by weight, viz.—

Nitroglycerin	100 lbs.
Dinitrotoluene	20 lbs.
Sodium nitrate	655 lbs.
Flour	80 lbs.
Middlings	60 lbs.
Sulphur	85 lbs.

The ingredients are prepared for mixing as follows:—

The sodium nitrate, flour, middlings and sulphur are first thoroughly dried, and after being carefully weighed, are thoroughly mixed together, preferably by means of a mixing machine.

The nitroglycerin and dinitrotoluene are first carefully weighed and then stirred together in a wooden, copper or lead tank by means of a wooden stick or paddle until all of the dinitrotoluene is dissolved in or is united with the nitroglycerin.

The solution of the dinitrotoluene in the nitroglycerin is then poured into the mixture of sodium nitrate, flour, middlings and sulphur, preferably while the latter is in the mixing machine, and the mixing machine is operated until the nitroglycerin-dinitrotoluene solution becomes thoroughly absorbed or incorporated in the sodium nitrate, flour, middlings and sulphur mixture.

After being put through the mixing machine, the product is then sifted and given an additional mixing with a wooden shovel. It is then in the form of powder and is ready to be packed in paper cartridges, as is customary. The cartridges may be of any size. They should be dipped in paraffin

wax before being filled, and after they are filled they should be redipped in paraffin wax. This will seal the ends of the cartridges and prevent the powder from absorbing moisture and from deteriorating, so long as the cartridges are kept in a cool dry place.

The addition of the dinitrotoluene to the nitroglycerin lowers the freezing point of the latter from about 48° F. to several 10 degrees below 0° F. This makes the powder very handy and useful, as it can be used regardless of climatic conditions, and it does not have to be thawed the way ordinary nitroglycerin powder does. Furthermore, 15 the addition of dinitrotoluene to the nitroglycerin, while not weakening the powder, make it safe for handling and for transportation, and gives it the quality of retaining its strength for an indefinite period of 20 time, and also makes it a comparatively cheap product.

What is claimed is:

1. A blasting powder composed of a solution of dinitrotoluene in nitroglycerine, absorbed in a powdered body containing 25 sodium nitrate, flour, middlings, and sulphur.
2. A blasting powder composed of nitroglycerin, dinitrotoluene, sodium nitrate, flour, middlings, and sulphur.
3. A blasting powder composed of from 30 10% to 20% of a solution of dinitrotoluene in nitroglycerin, absorbed in a powdered mixture of sodium nitrate, flour, middlings, and sulphur.
4. A blasting powder composed of 10% 35 of nitroglycerin, 2% of dinitrotoluene, 65.5% of sodium nitrate, 8% of flour, 6% of middlings, and 8.5% of sulphur.

In testimony whereof I have hereunto set my hand.

PETER N. STANKOVITCH.
